UNITED STATES PATENT OFFICE.

JOHN H. BARR, OF NEW YORK, N. Y., ASSIGNOR TO REMINGTON TYPEWRITER COMPANY, OF ILION, NEW YORK, A CORPORATION OF NEW YORK.

TYPE-WRITING MACHINE.

1,153,668.

Specification of Letters Patent. Patented Sept. 14, 1915.

Application filed January 21, 1915. Serial No. 3,474.

To all whom it may concern:

Be it known that I, JOHN H. BARR, citizen of the United States, and resident of the borough of Manhattan, city of New York, in the county of New York and State of New York, have invented certain new and useful Improvements in Type-Writing Machines, of which the following is a specification.

10 My present invention relates to ribbon mechanism for typewriting machines and its general object is to provide improved mechanism of the character specified.

More specifically one object of the invention is to provide new and improved means for varying the vibratory movement of the ribbon so that its different widthwise portions or color fields may be employed at will.

Another object is to provide novel means 20 for dispensing entirely with the use of the ribbon; and a still further object is to provide novel ribbon stop devices.

To the above and other ends my invention consists in the features of construction, combinations of devices and arrangements of parts hereinafter described and particularly pointed out in the claims.

In the accompanying drawings, Figure 1 is a side elevation partly in section of a No. 30 10 Remington typewriting machine embodying the preferred form of my invention, parts of the machine being omitted and parts broken away. Fig. 2 is a fragmentary front elevation showing indicating devices 35 and a finger piece and associate parts for controlling the ribbon mechanism. Fig. 3 is a transverse vertical sectional view taken on a plane indicated by the dotted line $x-x$ in Fig. 1 and looking forward. Fig. 4 is an 40 enlarged vertical sectional view taken on a plane indicated by the dotted line $y-y$ in Fig. 3 and looking in the direction of the arrow at said line. Fig. 5 is an enlarged perspective view of the ribbon vibrating and 45 controlling mechanism. Fig. 6 is a plan view partly in section of certain parts of the ribbon vibrating and controlling mechanism. Fig. 7 is a horizontal sectional view taken on a plane indicated by the dotted line $z-z$ 50 in Fig. 3.

As appears from Figs. 1 and 3 the main frame of the machine comprises a base 1, posts 2 and a top plate 3 which support fixed guide rails 4 on which runs a carriage 55 truck 5. A platen 6 is mounted in a platen

frame 7 which is shiftably connected with said truck by devices 8 so that said platen frame can be moved up and down to shift the platen and thereby change case. Said platen frame comprises a cross bar 10 on 60 which is journaled a roller 11 that is adapted to run on a shift rail 12 supported by upright arms 13 rising from a transverse bar 14 which is supported by upright arms 15, each arm 15 being pivoted at its lower end at 16 to a lever 17 provided with a shift key 18. The platen normally stands in its lower case position as shown in Fig. 1 but may be raised or shifted to upper case position by depressing either of the shift keys 18. The rail 12, cross bar 14 and uprights 13 and 15 constitute a shifting frame for controlling the shifting movements of the platen to operate either of the shift keys 18. Printing key levers 19 are provided with 70 keys 20 and are connected by links 21 with sub-levers 22, said sub-levers in turn being connected by links 23 with front-strike type bars 24 mounted on hangers 25 secured to a stationary segmental support 26. A universal bar 27 underlies the key levers and is supported on arms 28 depending from crank arms 29 which project rearward from a transverse rock shaft 30 having end pivots supported in the sides of the base. Projecting from said rock shaft near its middle 75 is an arm 31 which is connected by a link 32 with certain of the escapement devices (not shown) but which are of ordinary construction.

Ribbon spools 33 are supported one at each side of the machine below the top plate on shafts 34 and a ribbon 35 is wound on said spools and led upward therefrom through openings in the top plate, thence over stationary guides 36 and through guide openings in the head or upper portion of a ribbon carrier or vibrator comprising a pair of parallel wire guide loops 37 rising from a body portion 38, said vibrator being arranged about centrally between said stationary guides. Means for turning the spools in alternation to feed the ribbon longitudinally back and forth operate on the shafts 34 which bear in lugs 39 depending from the top plate and extending fore and aft of the machine. The ribbon spools are supported on the front ends of these shafts while their rear ends carry beveled pinions 40 which are adapted to mesh with beveled pinions 41 100 105 110

mounted on a ribbon driving shaft 42, one near each end. Said driving shaft is connected through intermeshing beveled pinions 43 and 44 with a spring drum 45 in such a way that when the carriage is drawn leftward under the pull of the spring drum with which it is connected by a band or strap 46, the ribbon driving shaft will be turned, causing a turning of one or the other 10 of the ribbon spools and the consequent longitudinal feeding of the ribbon. Means preferably of the usual Remington construction are provided for moving the driving shaft 42 back and forth endwise to cause 15 an alternate engagement of the pinions 40 by their associate driving pinions 41, thus reversing the direction of the ribbon feed.

The lower end of the ribbon vibrator 37, 38 is pivotally connected at 47 to the horizontally 20 disposed arm 48 of a bell crank lever 49 which at best appears in Figs. 3 and 5 further comprises a downwardly extending angular arm 50 and a cross arm or brace 51 connecting the two arms and stiffening the 25 member as a whole. The arm 48 divides into two branches which terminate in ears that fit over a rod 52 and bear pivotally thereon, said rod providing a fulcrum for the bell crank. The rod 52 is mounted on 30 a bracket 53 that is secured by screws 54 to the shift rail 12 and comprises a portion extending rearward below the shift rail and a forwardly and upwardly inclined portion which is provided with a tongue or lip 55 into which is threaded a headed screw 56. This screw serves as a guide for the ribbon 35 vibrator, the sheet metal body portion 38 whereof is formed with a slot 57 which fits over the screw and cooperates with the same 40 to guide the vibrator when it is moved up and down during printing operations. The top of said slot also may coöperate with the screw, especially when the platen is in shifted position, to limit the downward 45 movement of the vibrator. At its sides the bracket 53 terminates in upstanding fingers which assist in guiding the ribbon between the spools. The vibrator, the operating lever or bell crank and the guiding and supporting member or bracket 53, are, together 50 with the bell crank brace 51, specifically the invention of Edwin E. Barney, being disclosed and claimed in his application, Sr. No. 2,351, filed January 15, 1915, and are 55 not therefore claimed *per se* by me.

Devices for actuating the operating lever or member 49 are mounted on a bracket 58 which, as shown in Fig. 3, is detachably secured by screws 59 to the rear of the type 60 bar support 23. Said bracket has a downward extension 58^a slotted to receive one of the screws 59. The slots in the bracket 58 which receive the screws 59 are open at their lower ends so that by loosening the screws 65 the bracket 58, together with the parts which

it supports, may be vertically adjusted. Said bracket is provided with rearwardly bent parallel ears 60 which receive a rod 61 on which the actuating devices are pivotally mounted. The construction of this rod is 70 best shown in Fig. 7 from which it appears that the rod is provided with a threaded portion 62 and is reduced slightly in diameter at one side of the threaded portion. At its opposite end the rod has a nick 63 by 75 which said rod may be screwed into the bracket 58, one ear 60 whereof is formed with a threaded hole to coöperate with the threaded portion 62. After the rod is threaded in place a locking nut 64 may be 80 screwed on the portion 62 until it abuts the outer face of the ear 60, thus securing or locking the rod in fixed relationship with the bracket.

In the course of the assembling of the rod 85 61 on the bracket the parts for which said rod provides a pivot are also assembled in place. These parts are best illustrated in Figs. 3 to 5 and 7 and comprise two actuators or levers 65 and 66 which have a 90 common pivot being arranged to turn or fulcrum on the rod between the ears 60. The lever or member 65 is provided near its lower end with a cross portion 67 which terminates in forwardly bent ears 68; while the lever 66 has a cross portion 69 terminating in rearwardly bent ears 70. The two sets of ears are perforated so that the rod 61 may pass through them. The cross portions 69 and 67 are of such length that the ears 70 are embraced loosely between the ears 68 while these latter ears are loosely confined between the ears 60 of the bracket 58. The lever 65 is constantly connected with the downwardly extending arm 50 of the operating bell crank by a link 71, while the lever 66 is constantly connected to the arm 50 by a link 72. The link 71 is above the link 72 and at its forward end is pivotally connected as by a shoulder screw 73 with an ear 74 bent forward from the side of the lever 65 at its upper end. The rear end of the link 71 is pivotally connected by a shoulder screw 75 with an ear 76 bent rearward from the arm 50 about midway of its length. The link 72 is pivotally connected at its forward end by a shoulder screw 77 with the lever 66, said shoulder screw being threaded into an ear 78 bent forward from the lever 66 somewhat below its upper end. The rear end of the link 72 is pivotally connected by a shoulder screw 79 with an ear 80 bent backward from the arm 50 at its lower end, said ear 80 being at the opposite side edge of said arm from the ear 76. The links 71 and 72 incline downward and rearward from their respective pivotal connections 73 and 77 so that they are at angles to a horizontal line passing through these pivots. Said pivots dur- 125 130

ing the platen shifting operation remain stationary since the levers 65 and 66 are mounted on a stationary support. During the shift the rear ends of said links are 5 moved upward, being carried by the operating lever which is supported from the platen shifting frame. The links are so disposed that during the platen shifting operation they cross the horizontal or median lines 10 and at the end of such operation are at the same angle to said lines but above them as normally they are below them. It will be observed that as the result of the platen shifting operation the ribbon vibrator operating lever and links are moved or shifted while the elements of the ribbon vibrating mechanism below said links are not affected by the shift. It will be observed that the pair of links 71 and 72 are at all times or 15 20 constantly connected to the parts linked together by the links, viz., the arm 50 and the respective levers or actuators 65 and 62, as distinguished from a construction like that of my prior Patent No. 1,016,927, granted 25 Feb. 13, 1912, wherein a pair of links are shown in combination with devices for at will making and breaking their connection with one of the two parts or elements which they link together. It will also be noted 30 that the two key operated actuators or levers 65 and 66 are constantly connected independently of each other to the vibrator.

While the actuators 65 and 66 are both constantly connected with the operating 35 lever, means are provided for rendering them separately or alternately effective at will to operate said lever, said means comprising a rocking frame or actuating lever member designated as a whole by the reference numeral 81. The frame 81 is rectangular in shape and comprises a sheet metal portion bent into a U-shape and inverted, providing a top 82 and parallel side portions 83, the side portions being connected 40 at their lower ends by a cross rod 84. The side portions are perforated and reinforced with bosses or hubs 85 to fit over and bear both rotatably and slidably on the rod 61, 62, outside of the ears 60, the frame 81 45 being thus mounted co-axially with the actuators 65 and 66. The upper portion 82 of the frame is rectangular in shape, as best shown in Fig. 6. This rectangular part is cut out providing an opening or slot 86 near 50 the right-hand side and a smaller opening 87 at the left-hand forward corner. Between these openings at the front side is a triangular lug 88 which approaches closely 55 a lug or thickened portion 89 at the left-hand rear corner of the frame, the space 60 between the lugs 88 and 89 providing a narrow opening, passage-way or throat 90 connecting the slots 86 and 87 and within which the upper portions of the levers 65 and 66 65 are adapted to be separately disposed or

loosely confined when it is desired to render them operative. The forward edge 91 of the lug 89 is adapted to operate as an actuating surface. The construction is such that by effecting a relative shifting movement 70 between the frame 81 and the actuators 65 and 66 either actuator may be brought within the passage-way 90 and thereby rendered operative, being swung forward operatively when the frame is rocked, while the other 75 lever is left free or inoperative. Thus to rock the frame an actuating finger or arm 92 is fixed as by rivets 93 to the central arm 81 on the rock shaft 30, said finger 92 being adapted to act against the rod 84 to swing the frame 81 pivotally about the rod 61 as a center and co-axially with the levers 65 and 66 whatever may be the position of said frame endwise of said rod.

In the present instance the relative shift 85 or resetting between the frame 81 and the two actuators is preferably effected by shifting the frame endwise back-and forth on the rod 61, so as to select the actuator to be operatively vibrated. Thus to shift or variably move the frame 81 endwise, hand operated means are provided comprising as 90 shown in Figs. 1, 2, 3 and 5 a link or arm 94 curved upward at its inner end and terminating in a forwardly bent portion which 95 engages loosely in a slot formed in a lateral ear 95 projecting outward from the left-hand side portion 83 behind the pivot rod 61, so that vibratory movements of the frame 81 100 will only slightly affect the link 94. The outer or left-hand end of the link or bar 94 is pivotally connected at 96 with a crank arm 97 fixed to and projecting downward from the rear end portion of a rock shaft 98 extending fore and aft of the machine at 105 its left-hand side. Behind the crank arm the rock shaft bears in an angular bracket or arm 99 which is secured by screws 100 to the type bar segment 26. The forward end portion of the rock shaft bears in a plate 110 110 115 120 125 130 135 140 145 150 155 160 165 170 175 180 185 190 195 200 205 210 215 220 225 230 235 240 245 250 255 260 265 270 275 the present instance is preferably a bi-color ribbon, the upper stripe or field α being black and the lower stripe or field β being red. When the pointer 108 is opposite the middle indicating mark the shaft 98 will be blocked against further turning movement in clockwise direction by a stop 109 which is at this time in contact with the stop end 110 of a member 111 which is curved to partly surround the shaft 98 and is pivoted at 112 to the adjacent corner post 2. A finger piece 113 is provided for conveniently swinging up the stop member 111 so as to lift the stop 109 out of the path of the stop 109 and permit further turning of the shaft 98 until the pointer 108 is brought opposite the top indicating mark 107 at which time the ribbon throw changing parts controlled by the button 103 will be adjusted so that they will be inactive at printing operations, or otherwise expressed, will be in mimeograph position as hereinafter more fully explained. Thereafter during turning of the finger button in opposite or counter-clockwise direction the stop 109 will pass from under the stop end 110, permitting the stop member 111 to drop down by force of gravity until arrested by the engagement of the end portion 110 with a collar 114 which may be fixed to the rock shaft 98 behind the plate 101. The stop 109 projects radially beyond the periphery of this collar and its path is normally intercepted by the stop end 110 so that turning movement of the shaft 98 to render the ribbon throwing devices inoperative is impossible unless the stop 109 is lifted up out of the path of the stop 109. In order positively to limit the different extents of throwing movement of the ribbon, stop devices are provided comprising, as best shown in Figs. 4, 5 and 6, a stop plate 115 which is arranged on top of the usual spacing plate 116 secured to the upper face of the type bar segment 26. The stop plate 115 is provided with a longitudinal slot 117 which receives a headed screw 118 by which the plate is adjustably secured to its stationary support, viz., the segment 26. The rear end of the plate 115 is turned down to provide a vertical stop face proper 115 a which is always in the path of the forward edge of the part 82 of the vibratory member or frame 81 and always arrests said frame at the same point in its movement. The front end of the plate 115 is narrowed to provide a finger 115 b which is just wide enough to pass between the upper end portions of two adjacent hanger washers 119 secured in place as usual by screws 120 of the hangers. This arrangement prevents the plate 115 from skewing. When the screw 118 is loosened the only movement of which the plate is capable is a straight fore and aft one. The screw and slot connection 118, 117 of the stop plate with its support permits

fine adjustment of the stop plate when the parts are assembled but after such adjustment the stop plate is set rigidly on its stationary support by tightening the screw 118 and thereafter there is no variation in or adjustment of the fixed or stationary stop which is maintained in a single unvarying position for the varying throws or vibratory movements of the ribbon carrier, as will be better understood from what follows.

Assuming the parts are adjusted as in Figs. 3, 5 and 6, it will be understood that when a printing key is depressed the shaft 30 will be rocked as usual and will cause the finger 92, acting against the rod 84, to swing the frame 81 on its fulcrum. The upper portion of the frame moving forward will actuate the lever 66 whose upper end at this time is embraced within the passage-way 90 so that the edge 91 will act to push said lever 85 forward, the lever 66 becoming in effect a part of the frame 81. At this time the lever 65 will be in the opening 86 and will be inactive although it will swing idly forward as a result of the movement imparted to the operating lever through its connection 72 with the lever 66. As a result of this movement of the operating lever the vibrator will be lifted to interpose the printing portion of the ribbon in the path of the actuated type bar. The parts are so proportioned and adjusted that when the front edge of the part 82 strikes the stop 115 a , thus positively arresting the vibrator and connected train of actuating devices, the upper edge portion or field α of the ribbon will be presented opposite the printing point. This same extent of movement will be communicated at each vibratory movement of the ribbon as long as the parts are maintained adjusted as described so that type impressions will follow a straight path longitudinal of and about central of the upper field α .

When it is desired to use the lower ribbon field β the finger button 103 is turned counter-clockwise acting through the rock shaft 98, crank arm 97 and bar or link 94 to slide the frame 81 bodily rightward until its upper portion reaches the position indicated by dotted lines 82' in Fig. 6. The frame will be maintained in this new position as in the previous position by the detent devices 105, 106. As a result of this adjustment the passage-way 90 will be caused to embrace the upper end of the lever 65 while the lever 66 will be located in the opening 87. Consequently when the frame 81 is actuated during printing operations the edge 91 acting against the lever 65 will operate the same and the motion from said levers will be transmitted through the link 71 to the operating lever 49. At the start the edge 91 will be in contact with the lever 66, but the motion of this lever at this time will be so rapid, owing to the fact that it is being pushed by the arm 130

50 which is being pulled by the link 71, that the lever 66 will move forward away from the edge 91. As before, the movement of the parts will be arrested by the contact of the 5 edge of the part 82 with the stop 115^a, but though the movement of the frame 81 is constant the movement transmitted from it through the lever 65 to the vibrator will be greater than the movement transmitted 10 through the lever 66 for the reasons that the lever 65 is longer and transmits a greater movement to the link 71 than the lever 66 transmits to the link 72 and also because the link 71 acts closer to the fulcrum of the operating lever than does the link 72. The parts are so proportioned and adjusted that as a result of the longer throw transmitted to the vibrator the lower ribbon field *b* will be presented to the types. Both in this adjustment of the parts and in the prior described adjustment of the parts they will be restored to normal position chiefly by gravity when the printing keys are released although the usual rock shaft spring (not shown) will act on the rock shaft 30 and finger 92 as well as on the universal bar to restore them.

When it is desired to set the parts for mimeographing the stop member 111 is lifted as described and the finger piece 103 turned until the pointer 108 is brought opposite the top indicating mark 107. This movement of the rock shaft transmitted to the frame 81 through the described train of 35 connections will cause said frame to be slid bodily leftward along its fulcrum rod 61 until it is brought to the position indicated by the dotted line 82" in Fig. 6. As a result of this adjustment both levers 65 and 66 40 will be maintained simultaneously in the opening 86 so that at printing operations the frame 81 will be caused to swing idly on its pivot without affecting either lever 65 or 66, which levers, together with the ribbon 45 vibrator and operating lever, will remain motionless in normal position so that the types may strike against the paper or worksheet on the platen without the ribbon being interposed in their paths. The adjustments 50 may be such that the normal position of the vibrator in mimeograph condition may be somewhat lower than when the ribbon is being used.

Various changes may be made without departing from the spirit and scope of my invention.

What I claim as new and desire to secure by Letters Patent, is:—

1. In a typewriting machine, the combination of a ribbon vibrator, and means for variably actuating said vibrator, said means comprising two actuators both constantly connected independently of each other to said vibrator.

65 2. In a typewriting machine, the combi-

nation of a ribbon vibrator, two actuators for variably actuating said vibrator, both actuators being constantly connected thereto, and a settable device having an unvarying throw for operating said actuators in 70 alternation.

3. In a typewriting machine, the combination of a ribbon vibrator, a plurality of key operated actuators constantly connected to said vibrator, and means for rendering said actuators separately effective at will. 75

4. In a typewriting machine, the combination of a ribbon vibrator, a plurality of key operated actuators constantly connected to said vibrator and adapted to throw said 80 vibrator different extents, and means for rendering said actuators separately effective at will, said means comprising a settable device having an unvarying throw.

5. In a typewriting machine, the combination of a ribbon vibrator, a plurality of key operated actuators constantly connected to said vibrator and adapted to throw said 85 vibrator different extents, and means for rendering said actuators separately effective 90 at will, said means comprising a settable device having an unvarying throw, and a stationary stop for arresting said device at the end of its throw.

6. In a typewriting machine, the combination of a ribbon vibrator, a plurality of key operated actuators constantly connected to said vibrator, and means for rendering said actuators separately effective at will and also for rendering said actuators ineffective 95 at the same time when the keys are operated. 100

7. In a typewriting machine, the combination of a ribbon vibrator, an operating member to which said vibrator is connected, 105 a plurality of key operated actuators constantly connected to said member, and means for rendering said actuators separately effective at will.

8. In a typewriting machine, the combination of a ribbon vibrator, an operating member to which said vibrator is connected, a plurality of key operated actuators constantly connected to said member, and means for rendering said actuators separately effective at will and also for rendering said actuators ineffective at key operations so that the vibrator will be inactive. 110 115

9. In a typewriting machine, the combination of a ribbon vibrator, and means for variably actuating said vibrator, said means comprising two levers adapted to throw said vibrator different extents, both said levers being constantly connected to said vibrator. 120 125

10. In a typewriting machine, the combination of a ribbon vibrator, an operating lever connected with said vibrator, two other levers constantly connected with said operating lever and adapted to move it dif- 130

- ferent extents, and key connections to said two other levers comprising means for at will rendering said two other levers effective in alternation.
- 5 11. In a typewriting machine, the combination of a ribbon vibrator, an operating lever connected with said vibrator, two other levers constantly connected with said operating lever and adapted to move it different extents, keys, and means between said keys and said two other levers for at will rendering said two levers alternately effective and also for breaking the effective connection between said keys and said two other levers.
- 10 12. In a typewriting machine, the combination of a ribbon vibrator, and means for variably actuating said vibrator, said means comprising two actuators for said vibrator, and a frame for operating said actuators, said frame and said actuators being relatively shiftable.
- 15 13. In a typewriting machine, the combination of a ribbon vibrator, and means for variably actuating said vibrator, said means comprising two levers constantly connected to said vibrator, an actuating lever frame for operating said levers, and means for effecting a relative shift between said actuators and said lever frame to bring said levers into use in alternation.
- 20 14. In a typewriting machine, the combination of a ribbon vibrator, an operating member connected therewith, two levers both constantly connected to said member, and means for rendering said levers separately operative to move said vibrator, said means comprising a lever frame having a constant throw, and devices for effecting a relative shift between said levers and said lever frame.
- 25 15. In a typewriting machine, the combination of a ribbon vibrator, two actuators for said vibrator, a lever frame pivoted between its ends, and at one end loosely embracing said actuators, a key operated device engageable with the other end of said lever frame, and hand actuated means for effecting a relative shift between said lever frame and said actuators at will to operatively connect the lever frame with said actuators in alternation.
- 30 16. In a typewriting machine, the combination of a ribbon vibrator, two actuators constantly connected therewith, a lever frame provided with two openings and a connecting passage-way or throat, the lever frame being shiftable to cause the throat to engage with one or the other of said actuators while the other actuator is idle in one of said openings, said frame being further shiftable to cause one of said openings to receive both said actuators at the same time and thereby to render said frame inoperative on said vibrator.
- 35 17. In a typewriting machine, the combination of a ribbon vibrator, two levers for operating the same, and an actuating lever frame provided with slots or openings and with a connecting passage-way, said frame being shiftable to receive both said levers simultaneously in one of said slots to render said frame inactive.
- 40 18. In a typewriting machine, the combination of a ribbon vibrator, an operating lever connected therewith, two levers both constantly connected to said member, and means for rendering said levers separately operative to move said vibrator different extents.
- 45 19. In a typewriting machine, the combination of a ribbon vibrator, an operating member connected therewith, two levers both constantly connected to said member, and means for rendering said levers separately operative to move said vibrator different extents, said means comprising a settable lever frame having a constant throw.
- 50 20. In a typewriting machine, the combination of a ribbon vibrator, an operating member connected therewith, two levers both constantly connected to said member, and means for rendering said levers separately operative to move said vibrator different extents, said means comprising a settable lever frame having a constant throw, and a stop for arresting said lever frame at the end of its throw.
- 55 21. In a typewriting machine, the combination of a ribbon vibrator, a bell crank to which said vibrator is connected, two actuating levers, two links each connecting one of said actuating levers constantly with said bell crank, hand controlled means for rendering said levers alternately effective, and key devices operative on said means.
- 60 22. In a typewriting machine, the combination of a ribbon vibrator, a pair of actuators constantly connected with said vibrators, a controlling member for said actuators, hand operated means for moving said controlling member back and forth in opposite directions independently of said vibrator to render said actuators alternately effective, and other hand operated means for moving said member in another direction to move said vibrator.
- 65 23. In a typewriting machine, the combination of a ribbon vibrator, a pair of actuators therefor, a member settable to operate said actuators in alternation, printing keys, and connections between said printing keys and said member, said connections being at all times effective on said member.
- 70 24. In a typewriting machine, the combination of a ribbon vibrator, a pair of actuators therefor, a member settable to operate said actuators in alternation, printing keys, and connections between said printing keys and said member, said connections be-
- 75 80 85 90 95 100 105 110 115 120 125 130

ing at all times effective on said member, said member also being settable in a position where it will be ineffective on said actuators when said printing keys are operated.

5 25. In a typewriting machine, the combination of a ribbon vibrator, a pair of levers connected therewith, a lever frame for actuating said levers, means for setting said lever frame so that it will be effective on 10 said levers in alternation, printing keys, and connections between said printing keys and said lever frame.

26. In a typewriting machine, the combination of a ribbon vibrator, a pair of levers 15 for actuating said vibrator, a fulcrum rod for said levers, a lever frame also mounted on said fulcrum rod, means for sliding said frame endwise on said fulcrum rod to render it alternately effective on the levers of said 20 pair, and means for communicating pivotal movements to said lever frame on said fulcrum rod as an axis to actuate the levers of said pair.

27. In a typewriting machine, the combination of a ribbon vibrator, a pair of levers 25 for actuating said vibrator, a fulcrum rod for said levers, a lever frame also mounted on said fulcrum rod, means for sliding said frame endwise on said fulcrum rod to render 30 it alternately effective on the levers of said pair, and means for communicating pivotal movements to said lever frame on said fulcrum rod as an axis, said lever frame being also settable in a position where the 35 pivotal movements of said lever frame will be ineffective to actuate the levers of said pair.

28. In a typewriting machine, the combination of a ribbon vibrator, a pair of levers 40 for actuating the same, a fulcrum rod on which said levers are mounted, a lever frame also mounted on said fulcrum rod and having a portion embracing said pair of levers, said portion including a narrow passage- 45 way, means for moving said lever frame endwise on said fulcrum rod so as to bring said passage-way into alternate engagement with the levers of said pair, printing keys, and connections between said printing keys 50 and said lever frame for turning it on said fulcrum rod as an axis.

29. In a typewriting machine, the combination of a ribbon vibrator, a pair of levers 55 for actuating the same, a fulcrum rod on which said levers are mounted, a lever frame also mounted on said fulcrum rod and having a portion embracing said pair of levers, said portion including a narrow passage-way, means for moving said lever frame 60 endwise on said fulcrum rod so as to bring said passage-way into alternate engagement with the levers of said pair, printing keys, and connections between said printing keys and said lever frame for turning it on said

fulcrum rod as an axis, said lever frame being also settable in a position where both levers of said pair will be outside of said passageway, the lever frame being thereby rendered ineffective on said levers when said printing keys are actuated. 65

30. In a typewriting machine, the combination of a ribbon vibrator, an operating lever, two actuators, links connecting said actuators constantly with said operating lever, a lever frame settable in positions to 70 alternately operate said actuators, printing key levers, a universal bar operative thereby, a rock shaft connected to said universal bar, and a projection on said rock shaft for operating said lever frame. 75

31. In a typewriting machine, the combination of a ribbon vibrator, an operating lever, two actuators, links connecting said actuators constantly with said operating lever, a lever frame settable in positions to 80 alternately operate said actuators, a key operated universal rock shaft having a projection engageable with said lever frame to give it an unvarying throw, and a stationary stop coöperative with said lever frame 85 at the end of its throw. 90

32. In a typewriting machine, the combination of a ribbon vibrator, two actuators constantly connected therewith, a lever frame pivoted between its ends and at one 95 end loosely embracing said actuators, a key operated device engageable with the other end of said lever frame, and hand actuated means for shifting said lever frame at will to operatively connect it with said actuators 100 in alternation.

33. In a typewriting machine, the combination of a ribbon vibrator, a member having a constant throw, a fixed stop with which said member always coöperates at 105 the end of its throw, and variable connections between said member and said vibrator.

34. In a typewriting machine, the combination of a ribbon vibrator, a member having a constant throw, a fixed stop with which said member coöperates at the end 110 of its throw, two actuators for moving said vibrator different extents, and means for effecting a relative shift between said member and said actuators to render said actuators operative in alternation. 115

35. In a typewriting machine, the combination of a ribbon vibrator, adjustable vibrator operating means for moving it different distances, and stationary stop means for positively limiting the respective distances through which the vibrator is moved. 120

36. In a typewriting machine, the combination of a ribbon vibrator, means for throwing the same different extents comprising two actuators constantly connected with said vibrator and alternatively effective 125

thereon, and stationary stop means for positively arresting said actuators at the end of their respective effective movements.

37. In a typewriting machine, the combination of a platen, a platen shifting frame, a ribbon vibrator, an operating lever to which said vibrator is connected, said operating lever being mounted on said platen shifting frame, a pair of levers, a stationary fulcrum rod on which said levers are mounted, links connecting said pair of levers with said operating levers, a lever frame mounted on said fulcrum rod, a key operated universal bar, connections between said universal bar and said lever frame, and means for variably setting said lever frame endwise to render said actuating levers alternately effective to variably move the ribbon vibrator at printing operations, said levers being quiescent when the platen, ribbon vibrator and operating lever are shifted but said links participating in said shifting movement.

38. In a typewriting machine, the combination of a platen, a platen shifting frame, a ribbon vibrator mounted to shift with said frame, a plurality of key operated actuators mounted independently of said frame and constantly connected with said vibrator, and means for rendering said actuators separately effective at will.

39. In a typewriting machine, the combination of a platen, a platen shifting frame, a ribbon vibrator, an operating member mounted on said frame and to which said vibrator is connected, a plurality of key operated actuators mounted independently of said frame and constantly connected to said member, and means for rendering said actuators separately effective at will.

40. In a typewriting machine, the combination of a shiftable platen, a ribbon vibrator, a bell crank to which said vibrator is connected, said vibrator and said bell crank being shiftable with said platen, two non-shiftable actuating levers, two links each connecting one of said actuating levers constantly with said bell crank, hand controlled means for rendering said levers alternately effective, printing keys, and connections between said printing keys and said means.

41. In a typewriting machine, the combination of a shiftable platen, a ribbon vibrator, an operating lever supporting said vibrator and shiftable with said platen, two non-shiftable actuating levers, links connecting said operating lever with said actuating levers, a non-shifting lever frame settable at will to coöperate with said actuating levers in alternation to throw the vibrator variable distances, printing keys, and connections between said keys and said lever frame.

42. In a typewriting machine, the combination of a shiftable platen, a ribbon vibrator, an operating lever supporting said vibrator and shiftable with said platen, two non-shiftable actuating levers, links connecting said operating lever with said actuating levers, a lever frame settable at will to coöperate with said actuating levers in alternation to throw the vibrator variable distances, printing keys, connections between said keys and said lever frame, and a stationary stop for arresting said lever frame being independent of the platen shift.

43. In a typewriting machine, the combination of a ribbon vibrator, an operating member connected therewith, a plurality of key controlled actuators constantly connected with said member and having an unvarying normal position, and settable means for rendering said actuators separately effective on said member, said vibrator remaining quiescent during the operations of setting and resetting said means.

44. In a typewriting machine, the combination of a ribbon vibrator, an operating member connected thereto, a key controlled universal bar, links operative by said universal bar and both constantly connected with said member, and settable means for at will rendering said links operative on said member to actuate said vibrator, said means being settable independently of movement of said vibrator.

45. In a typewriting machine, the combination of a ribbon vibrator, an operating member connected thereto, a key controlled universal bar, links operative by said universal bar and both constantly connected with said member, and devices settable independently of said links and of said vibrator for rendering said links separately effective at will.

46. In a typewriting machine, the combination of a ribbon vibrator, a pair of links constantly connected thereto, a pair of actuators one for each link, and means for selectively operating said actuators.

47. In a typewriting machine, the combination of a ribbon vibrator, an operating lever, a pair of links constantly connected to said lever, a pair of actuators one for each link, and means for selectively operating said actuators so that the links may be caused alternately to transmit movement to said operating lever and vibrator.

48. In a typewriting machine, the combination of a ribbon carrier, an operating lever, two links operative on one arm of said lever at different distances from its fulcrum, two levers operative each on one of said links, and means for vibrating said levers one at a time.

49. In a typewriting machine, the combination of a ribbon carrier, an operating

lever, two links operative on one arm of said lever at different distances from its fulcrum, two levers operative each on one of said links, and a common vibrating member for said levers, said levers and said vibrating member being relatively adjustable so that only one lever may be vibrated at a time.

50. In a typewriting machine, the combination of a platen, a platen shifting frame, 10 a ribbon vibrator, an operating lever mounted on said shifting frame, a key controlled universal bar, links constantly connected with said operating lever and operated by said universal bar, and settable means 15 mounted independently of said shifting frame for rendering said links separately effective.

51. In a typewriting machine, the combination of a ribbon vibrator, an operating 20 lever connected with said vibrator, two other levers constantly connected with said operating lever and adapted to move it different extents, and key connections to said two other levers comprising means for at will 25 rendering said two other levers effective in alternation, and a stationary stop coöperative with said means to limit the movements of said ribbon vibrator.

52. In a typewriting machine, the combination of a ribbon vibrator, an operating lever connected therewith, two levers both constantly connected to said member, means 30 for rendering said levers separately operative to move said vibrator different extents, 35 and a stationary stop coöperative with said means to limit the movements of said vibrator.

53. In a typewriting machine, the combination of a ribbon vibrator, a bell crank 40 to which said vibrator is connected, two actuating levers, two links each connecting one of said actuating levers constantly with said bell crank, hand controlled means for rendering said levers alternately effective, 45 key devices operative on said means, and a stop to limit the movement of said means when actuated by said key devices.

54. In a typewriting machine, the combination of a ribbon vibrator, a pair of actuators therefor, a member settable to operate 50 said actuators in alternation, printing keys, connections between said printing keys and said member, said connections being at all times effective on said member, said member 55 also being settable in a position where it will be ineffective on said actuators when

said printing keys are operated, and stop means coöperative to arrest said member at the end of its key actuated movements.

55. In a typewriting machine, the combination of a ribbon vibrator, a pair of levers connected therewith, a lever frame for actuating said levers, means for setting said lever frame so that it will be effective on said levers in alternation, printing keys, 60 connections between said printing keys and said lever frame, and stop means coöperative with said lever frame to arrest it at the end of its actuating movements.

56. In a typewriting machine, the combination of a ribbon vibrator, a pair of levers for actuating said vibrator, a fulcrum rod for said levers, a lever frame also mounted on said fulcrum rod, means for sliding said frame endwise on said fulcrum rod to 70 render it alternately effective on the levers of said pair, means for communicating pivotal movements to said lever frame on said fulcrum rod as an axis to actuate the levers of said pair, and a stop for limiting the pivotal 75 movements of said lever frame.

57. In a typewriting machine, the combination of a ribbon vibrator, a pair of actuators for said vibrator having a common pivot, a key actuated operating member co- 80 axial with said actuators, and means for relatively shifting said member and said actuators to cause said member to operate said actuators separately.

58. In a typewriting machine, the combination of a ribbon vibrator, an operating member connected with said vibrator, two levers constantly connected with said operating member and adapted to move it different 90 extents, keys, means extending to the front 95 of the machine for at will rendering the keys effective on said two levers in alternation, and stop devices including a pivoted stop effective on said means to prevent the simultaneous withdrawal of said levers from 100 action, said pivoted stop being movable by hand to permit such simultaneous withdrawal.

Signed at the borough of Manhattan, city of New York, in the county of New York, 105 and State of New York, this 20th day of January, A. D. 1915.
